Des. 216,561
Patented Feb. 10, 1970

216,561

BUILDING WALL PANEL

Thomas C. Colson, Overland Park, Kans., Terry E. De Witt, Independence, Mo., Robert P. Orr, Overland Park, Kans., and John T. Thurman, Independence, Mo., assignors to Butler Manufacturing Company, Kansas City, Mo., a corporation of Missouri

Filed Nov. 18, 1968, Ser. No. 14,514

Term of patent 14 years

Int. Cl. D25—01

U.S. Cl. D54—2

Fig. 1.

Fig. 2.

FIG. 1 is a front elevational view of a building wall panel embodying my new design, the break lines indicating interrupted length;

FIG. 2 is an end elevational view of same, the other end being substantially identical; and

FIG. 3 is an end perspective view of a fragmentary portion of the panel looking toward the front side thereof. We claim:

The ornamental design for a building wall panel, as shown and described.
